UNITED STATES PATENT OFFICE

2,440,021

CHAFE PANTIE

Pauline E. Rosenblatt, Cleveland, Ohio

Application March 12, 1946, Serial No. 653,723

7 Claims. (Cl. 128—149)

1

This invention relates in general to undergarments and, more particularly, to chafe panties adapted to be worn under girdles, foundation garments, etc. Panties of this type should permit ready access without dislocation or opening up of the girdle or foundation garment, snugly and smoothly fit the crotch without wrinkling or folding and eliminate creeping of the crotch and chafe shields.

The primary object of the invention is the provision of a chafe pantie of the type referred to above having front and rear portions, chafe shields attached to the lower portions of said front and rear portions and means attached to the bottom edge of the rear portion and the chafe shields adapted to yieldingly clutch in cooperation with the rear portion and chafe shields the thighs of a person wearing the pantie and yieldingly draw the chafe shields around such thighs and stretch the front and rear portions over the body of such person, all for the purpose of snug contact of the pantie with the body to insure proper absorption of body perspiration and secretion by the pantie.

Another object of the invention is the provision of a chafe pantie of the type referred to above having front and rear portions, a crotch portion connecting the central bottom portions of said front and rear portions, chafe shields attached to the crotch and the outer bottom portions of said front and rear portions, and means secured to the bottom portion of said rear portion and said chafe shields adapted to yieldingly clutch in cooperation with the rear portion and chafe shields the thighs of a person wearing the pantie, yieldingly draw the chafing shields around such thighs and yieldingly stretch the rear portion at its lower edge to release excessive pull in the crotch and smoothly fit the pantie over the body of such person, all for the purpose of a smooth but snug contact of the pantie with the body to insure proper absorption of body perspiration and secretion by the pantie.

Such objects, according to the invention, are attained by providing a pantie having front and rear portions united by a crotch and chafe shields with a pair of fastening means (hook and eye fasteners or similar devices) arranged so that each fastening means has its one member slidably supported on a strip of elastic secured at its ends to spaced points at the bottom edge at one side of the rear portion, and its other member attached to the edge of the respective chafe shield.

A further object of the invention therefore is 55 to provide a chafe pantie having front and rear portions united by a crotch and symmetri-

2

the provision of a chafe pantie having front and rear portions united by a crotch and symmetrically arranged chafe shields with a pair of attaching means, each of which embodies an attaching member slidably supported on a strip of elastic secured at its ends to spaced points of the bottom edge of the respective bottom side of the rear portion and another attaching member secured to the outer edge of the respective chafe shield.

10 In addition, the invention has certain other marked superiorities which radically distinguish it from presently known structures. These improvements or superiorities embodying certain novel features of construction are clearly set forth in the following specification and the appended claims; and a preferred form of embodiment of the invention is hereinafter shown with reference to the accompanying drawing forming part of the specification.

20 In the drawing:

Fig. 1 is a side perspective view of the chafe pantie shown applied to a female figure.

Fig. 2 is a front perspective view of the chafe pantie.

25 Fig. 3 is a rear perspective view of the chafe pantie.

Fig. 4 is a plan view of the several blanks forming the pattern of the chafe pantie; and

30 Fig. 5 is an enlarged fragmentary perspective view showing the shiftably supported attachment member and its supports.

Referring now in detail to the drawing, the body of open-sided chafe pantie 2, made of suitable knitted or netted material, embodies a front portion 3, a rear portion 4, a crotch member 5 and chafing shields 6, 6'. The front and rear portions are designed to cling snugly to the front and back of a wearer and have their top portions connected with each other by pieces of elastic 7, 7' and their central bottom portions sewn to the rectangularly shaped crotch member 5 made up of two superposed layers of material. To that end, front portion 3 includes a slightly wedge-shaped upper area 8, a sharply wedge-shaped lower area 9 adjoining said first area, which lower area is formed with a horizontally arranged straight bottom edge 10 and sewed to the corresponding edge 11 of crotch member 5, and rear portion 4 embodies an invertedly wedge-shaped upper area 12, adjoined by a sector-like lower area 14, slotted vertically at 15 to divide this area in left and right-handed sections 16 and 17 cooperating with chafe shields 6, 6' and crotch mem-

a person wearing the pantie and protecting the buttocks of such person.

The central portion 18 of the slit 15 in rear portion 4 is sewn to edge 19 of crotch member 5, which edge is opposite to edge 11 and, furthermore, edges 20 and 21 of slit 15 adjoining central portion 18 are attached to chafe shields 6, 6', also sewn to opposed edges 22, 22' of crotch member 5 and inclined edges 23, 23' of wedge-shaped lower area 9 of front portion 3, so that left and right-handed sections 16 and 17 of rear portions 4 together with chafe shields 6, 6' form leggins 24 which are split at their outside and thus provide proper chafe protection for the inside of the thighs of the wearer.

Each split legging 24 has the ends of its lower edge releasably and yieldingly secured to each other by means of a pair of fastening means 25, 26, member 25 of which is freely slidably supported on a strip of elastic 27 secured at its ends to spaced points at the bottom edge of the respective section 16 or 17 of rear portion 4, and member 26 of which is attached to the respective chafe shield. This arrangement effects a yieldingly clutching of the thighs of a person wearing the pantie, yieldingly stretches the rear portion and thus avoids excessive pull in the crotch and yieldingly stretches the chafing shields smoothly over the thighs of a person for proper absorption of body perspiration and secretion by crotch portion and chafing shields.

Fabrication of the body of chafe pantie 2 is effected by sewing edge 11 of crotch member 5 to straight bottom edge 10 of front portion 3, then sewing chafing shields 6, 6' to the respective side edges of the crotch member and the front portion and, finally, sewing the chafing shields to the respective edges of rear portion 4 and edge 19 of crotch member 5. In these sewing operations crotch member 5 is preferably stretched longitudinally and rear portion 4 is stretched in the area of its edges 20, 21 to provide the desired fullness in the pantie.

Having thus described my invention:

What I claim is:

1. In a chafe pantie a front member, a rear member including a top area and a sector-like bottom area having a radial slit therein, a crotch member extended into said slit and attached with one end to said rear member at the central portion of said slit, a pair of chafing shields attached to the crotch member and said front and rear members to form split leggins with said members, and resilient means for each of said leggins resiliently connecting the free ends of a legging to each other and to the bottom edge of the rear member at a point between the free ends of said legging to resiliently clutch the thighs of a person wearing the pantie and stretch the chafing shields and the bottom area of said rear member around the body of such person.

2. A chafe pantie as described in claim 1, wherein said resilient connecting means include cooperating fastening members, and a strip of elastic secured with its ends to spaced points of the bottom edge of said rear member said strip of elastic slidably mounting one of said fastening members the other one of said fastening members being attached to the respective chafing shield.

3. In a chafe pantie a front member, a rear member, a pair of chafing shields attached to said front and rear members forming slit leggins therewith, and resilient means for each

of said legging resiliently connecting the free ends of a legging to each other and to the bottom edge of the rear member at a point positioned between the free ends of said legging to resiliently clutch the thighs of a person wearing the pantie and stretch the chafing shields and the bottom portion of said rear member around the body of such person.

4. In a chafe pantie a front member, a rear member slit at its bottom to form said member with symmetrically arranged extensions, a pair of chafing shields, each attached to said front member and one of said extensions for forming slit leggins therewith, and resilient means for each of said leggins resiliently connecting the free ends of a legging to each other and to the bottom edge of the respective extension to resiliently clutch the thighs of a person wearing the pantie and stretch the chafing shields and extensions around the body of such person.

5. In a chafe pantie a wedge-shaped front member, an invertedly wedge-shaped rear member slit at its bottom portion to form said member with symmetrically arranged extensions, a pair of chafing shields, each attached to one side of said front member and the respective extension for forming slit leggins therewith, resilient means resiliently connecting the top portions of said front and rear members, and resilient means for each of said leggins resiliently connecting the free ends of a legging to each other and to the bottom edge of the respective extension to resiliently clutch the thighs of a person wearing the pantie and stretch the chafing shields and extensions around the body of such person.

6. In a chafe pantie a wedge-shaped front member, an invertedly wedge-shaped rear member slit at its bottom portion to form said member with symmetrically arranged extensions, a crotch member attached with one end to said rear member between the extensions thereof, a pair of chafing shields attached to the sides of said crotch member, said front member and the respective extensions to form said pantie with slit leggins, resilient means resiliently connecting the top portions of said front and rear members, and resilient means for each of said leggins resiliently connecting the free ends of a legging to each other and to the bottom edge of the respective extension to resiliently clutch the thighs of a person wearing the pantie and stretch the chafing shields and extensions around the body of such person.

7. A chafe pantie as described in claim 6, wherein each of the said resilient connecting means for said leggins consist of hook and eye members, and a strip of elastic, and wherein one of said members is slidably mounted on the strip of elastic the ends of which are attached to the bottom edge corners of the respective extension and the free corner edge of the respective chafing shield.

PAULINE E. ROSENBLATT.
